SURFACE TREATING MACHINE DRIVE BLOCK

Robert H. Kleemeier, Arden Hills, and Ronald O. Zemke,
Saint Paul, Minn., assignors to Minnesota Mining and
Manufacturing Company, St. Paul, Minn., a corpora-
tion of Delaware

Filed Mar. 18, 1968, Ser. No. 11,031

Term of patent 14 years

(Cl. D37—3)

FIG. 1

FIG. 2

FIG. 3

FIG. 5

FIG. 4

FIGURE 1 is a perspective view of the surface treating machine drive block of our invention, used for driving lofty fibrous polishing, scrubbing, or buffing pads;

FIGURE 2 is a top plan view thereof;

FIGURE 3 is a front elevational view thereof, the rear being a mirror image of the front;

FIGURE 4 is a side elevational view thereof; the other side being a mirror image;

FIGURE 5 is a bottom plan view thereof.

We claim:

The ornamental design for a surface treating machine drive block, substantially as shown and described.
